SPHERICAL LAMP WITH EASY HEAT DISSIPATION

CROSS-REFERENCE TO RELATED APPLICATIONS

The present application is a continuation of International Application No. PCT/KR2012/006898 filed on Aug. 29, 2012, which claims priority to Korean Application No. 20-2011-0007826 filed on Aug. 29, 2011, which applications are incorporated herein by reference.

TECHNICAL FIELD

The present disclosure relates to a spherical lamp that facilitates heat dissipation, and more particularly, to a spherical lamp that facilitates heat dissipation in which a light source using LEDs is sealed by a spherical cover and the heat dissipation structure is improved.

BACKGROUND ART

Recently, technologies for indoor illumination using an LED, which consume low amounts of power and have a long lifespan, and which is environmentally friendly as compared to existing fluorescent lights or incandescent lamps, have been developed.

Basically, LEDs may emit lights at various levels of illumination and in different colors according to the setting of the LEDs. However, since it is complicated to set such LEDs for use indoors in a home or the like, most LEDs are fabricated as a single-color product with white or daylight color.

However, an indoor light using such a single-color LED is merely an illuminance-controlled light and cannot be expected to enhance the interior effect. Thus, such an indoor light does not suit the needs of a market.

In the prior art, a structure capable of emitting plural colors in an LED illumination lamp is disclosed in Korean Patent No. 0961726.

However, the invention disclosed in Korean Patent No. 0961726 (hereinafter, simply referred to as a "prior art 1") has a structure in which, since a PCB board installed within a spherical cover having a diameter larger than that of the opening provided in the spherical cover should be introduced into the spherical cover through the opening, a flexible PCB must be used and heat generated from LEDs cannot be efficiently dissipated.

Accordingly, there is a problem in that the lifespan of the LEDs is shortened due to the generated heat.

That is, when an illumination light uses a spherical cover on a light source, LEDs as the light source are accommodated in the spherical cover. Accordingly, there are problems in that, since heat is not readily dissipated, the lifespan of the LEDs is shortened by the generated heat, and the use of the illumination light is limited due to the heat generation.

SUMMARY

The present disclosure has been made in an effort to solve the problems as described above, and the present disclosure provides a spherical lamp that facilitates heat dissipation, in which multi-colored light is implemented by LEDs to be used for illumination, the LEDs are installed within a spherical cover, and a heat dissipation structure is improved such that the heat dissipation effect can be enhanced.

2

In addition, the present disclosure provides a spherical lamp configured to facilitate heat dissipation which enables beautiful illumination through various illumination effects.

In order to solve the problems described above, there is provided a spherical lamp which facilitates heat dissipation. The spherical lamp includes: lower and upper substrates, on each of which a plurality of LEDs are mounted; a plate-shaped substrate support unit having bottom and top surfaces, to which the lower and upper substrates are coupled, respectively; lower and upper semi-spherical covers fixed to the bottom and top surfaces of the substrate support unit, respectively; a support unit coupled to a central portion of the top surface of the substrate support unit and exposed to the outside through a central portion of the upper cover; and a heat dissipation plate having a coupling portion provided on a bottom surface thereof, an end of the support unit being inserted into and fixed to the coupling portion.

In a spherical lamp that facilitates heat dissipation according to the present disclosure, a side portion of a substrate unit, that supports a substrate including a plurality of LEDs, is exposed to the outside of a spherical cover so that the heat generated from the LEDs is transferred to the outside above the spherical cover using a support unit capable of transferring heat upward, and a heat dissipation plate is coupled to the support unit to dissipate the heat generated from the LEDs. As a result, the heat dissipation effect of the LEDs in the lamp using the spherical cover may be enhanced to prevent the shortening of the lifespan of the LEDs.

In addition, in the spherical lamp that facilitates heat dissipation according to the present disclosure, illuminations of different colors may be implemented using the substrate support unit as a border therebetween, and the light emitted to the top side of the substrate support unit may be reflected by the heat dissipation plate to provide beautiful illumination.

BRIEF DESCRIPTION OF THE DRAWINGS

FIG. 1 is an exploded perspective view illustrating a spherical lamp that facilitates heat dissipation according to an exemplary embodiment of the present disclosure;

FIG. 2 is a cross-sectional view illustrating a configuration of the spherical lamp facilitated in heat dissipation according to the exemplary embodiment of the present invention in an assembled state;

FIG. 3 is a perspective view illustrating a configuration of an exemplary embodiment of a substrate support unit applied to the present disclosure; and

FIG. 4 is a cross-sectional view illustrating a configuration of an exemplary embodiment of a support unit and a coupling portion of a heat dissipation plate applied to the present disclosure.

DETAILED DESCRIPTION

Hereinbelow, a spherical lamp facilitated in heat dissipation according to exemplary embodiments of the present disclosure will be described in detail with reference to accompanying drawings.

FIG. 1 is an exploded perspective of a spherical lamp configured to facilitate heat dissipation according to an exemplary embodiment of the present disclosure, and FIG. 2 is a cross-sectional view illustrating a configuration of the spherical lamp of FIG. 2 in an assembled state.

Referring to FIGS. 1 and 2, a spherical lamp that facilitates heat dissipation according to an exemplary embodiment of the present disclosure includes: lower and upper

substrates **10** and **20**, each of which is provided with a plurality of LEDs (not illustrated); a disc-shaped substrate support unit **30** having a top surface and a bottom surface, to which the upper substrate **20** and the lower substrate **10** are coupled, respectively, the substrate support unit **30** including a plurality of coupling holes **31** and **32** formed vertically therethrough outside the lower substrate **10** and the upper substrate **20**; a hollow support unit **40** coupled to a central portion of the substrate support unit **30** and extending upward; a semi-spherical lower cover **50** including, at an end thereof, one or more fastening portions **51** which are adapted to be fastened to the coupling holes **31** so that the lower cover **50** is coupled to the bottom surface of the substrate support unit **30** where the lower substrate **10** is coupled; a semi-spherical upper cover **60** including, at a central portion thereof, a through hole **62** through which the hollow support unit **40** passes, and, at an end thereof, one or more fastening portions **61** which are adapted to be fastened to the coupling holes **32** so that the upper cover **60** is coupled to the top surface of the substrate support unit **30** where the upper substrate **20** is coupled; a lampshade **70** fitted on the hollow support unit **40** extending from the top surface of the upper cover **60**; and a disc-shaped heat dissipation plate **80** including, on a bottom surface thereof, a coupling portion **81** into which an end of the hollow support unit **40** extending above the lampshade **70** is inserted.

Reference numeral **90** which is not referred to above indicates a pendant which serves to fix the lamp to a ceiling.

Hereinafter, a configuration and a functional effect of the spherical lamp facilitating heat dissipation configured as described above according to an exemplary embodiment will be described in more detail.

First, the lower substrate **10** has a disc shape and is provided with plurality of LEDs on the bottom surface thereof in the installed state. The upper substrate **20** has a disc shape provided with a through hole at the central portion thereof and is mounted with a plurality of LEDs on the top surface thereof in the installed state.

Accordingly, the LEDs of the lower substrate **10** irradiate light downward and the LEDs of the upper substrate **20** irradiate light upward in which each of the LEDs may be configured to emit different colors.

The lower substrate **10** and the upper substrate **20** are fastened to the bottom surface and the top surface of the disc-shaped substrate support unit **30**, respectively, using fastening means such as bolts. The diameter of the substrate support unit **30** is larger than the diameters of the lower substrate **10** and the upper substrate **20** and a plurality of coupling holes **31** and **32** are formed through the substrate support unit **30** on the peripheral edge of the substrate support unit **30**.

The material of the substrate support unit **30** is a metal which is excellent in heat conductivity.

Accordingly, heat generated from the LEDs provided on each of the lower substrate **10** and the upper substrate **20** is transferred through the substrate support unit **30**.

A cylindrical support unit **40** is coupled to the central portion of the top surface of the substrate support unit **30**. The substrate support unit **30** and the support unit **40** may be configured separately or integrally.

The support part **40** is hollow to provide a space in which a wire that supplies power to the lower substrate **10** and the upper substrate **20** is provided. The wire is provided through the pendant **90**.

The support unit **40** is also made of a metal which is excellent in heat conductivity and serves to dissipate the heat from the substrate support unit **30** to the outside.

In the coupled state as described above, a lower cover **50** is coupled to the bottom surface of the substrate support unit

30. The lower cover **50** has a semi-spherical shape and may be made of a resin material which is transparent or has a predetermined color.

Along a circular end of the lower cover **50**, a plurality of fastening portions **51** are provided to protrude vertically at predetermined intervals. Each of the fastening portions **50** also protrudes laterally on the end of the vertically protruding portion so as to prevent the release of the fastening portions **50**.

10 The fastening portions **51** are inserted into coupling holes **31** provided in the substrate support unit **30** so as to fix the lower cover **50**.

In addition, the upper cover **60** has a semi-spherical shape and a through hole **62** is provided at the central portion of the upper cover so as to allow the support part **40** to pass therethrough. A plurality of fastening portions **61** are provided along the circular end of the upper cover **50**. The upper cover **60** may also be made of a resin material which is transparent or has a predetermined color.

20 The fastening portions **61** are inserted into the coupling holes **32** on the top side of the substrate support unit **30** such that the support unit **40** is coupled to the top surface of the substrate support unit **30** in a state where a part of the support unit **40** is exposed.

25 At this time, the lower cover **50** and the upper cover **60** are respectively coupled to the bottom and top sides of the substrate support unit **30** to form a spherical light source. An illumination lamp using a sealed light source does not facilitate heat dissipation. However, a lateral portion of the substrate support unit **30** is exposed to the outside between the lower cover **50** and the upper cover **60** and dissipation occurs through this portion.

30 FIG. 3 is a view illustrating a configuration of an exemplary embodiment of the substrate support unit **30**.

Referring to FIG. 3, the substrate support unit **30** is disc-shaped and provided with coupling holes **31** and **32** as described above. In order to facilitate the heat dissipation, a plurality of heat dissipation fins **33** may be provided on the side surface thereof.

35 When the circumferential surface of the substrate support unit **30**, which is provided with the heat dissipation fins **33**, is exposed to the outside between the lower cover **50** and the upper cover **60**, the heat generated from the LEDs provided on the lower substrate **10** and the lower substrate **20** may be emitted more efficiently through heat exchange with the air.

40 In addition, a lampshade **70** is fitted on a portion of the supporting unit **40** protruding to the outside through the through hole **62** on the upper cover **60**.

45 The lampshade **70** has a curvature to enclose the upper cover **60**, and the bottom side of the lamp shade **70** facing the upper cover **60** may be a reflective surface or a transreflective surface that partially reflects the light emitted from the LEDs of the upper substrate **20** and partially transmits the light.

50 The lampshade **70** may be made of a metal that facilitates heat dissipation to be used as a full reflective surface or made of a resin to be transreflective with respect to light.

The lampshade **70** is fitted on the support unit **40** and a part of the support unit **40** is exposed to the top side of the lampshade **70**. The exposed support unit **40** is inserted into 60 and fixed to a coupling portion **81** of the heat dissipation plate **80**. The coupling portion **81** is a recess that receives the support unit **40** and allows the heat of the LEDs, which is transferred thereto through the support unit **40**, to be transferred to the heat dissipation plate **80** and dissipated.

65 At this time, in order to ensure that the heat may be efficiently transferred from the support unit **40** to the heat dissipation plate **80**, the support part **40** and the coupling

portion **81** should be snugly coupled to each other. When a gap exists between the support part **40** and the coupling portion **81**, heat conductivity may be considerably reduced.

FIG. 4 is a cross-sectional view illustrating the heat dissipation plate and the coupling portion of the support unit.

Referring to FIG. 4, heat dissipation fins **82** may be provided on the bottom surface of the heat dissipation plate **80** to increase a heat dissipation area so as to enhance heat dissipation efficiency. The coupling portion **81** provided at the central portion of the bottom surface of the heat dissipation plate **80** has an inclined side surface such that the inner diameter of the coupling portion **81** increases toward the outside.

As described above, the coupling portion **81** is formed in a shape that allows the coupling portion **81**, which is made of a metal, to be readily fit on the support unit **40**, which is also made of a metal. Although omitted from the drawings, a fastening means such as a bolt may be inserted through the side wall of the coupling portion **81** to fix the support unit **40**.

In addition, a heat conducting sheet **83** is sandwiched between the top end of the support unit **40** and the top surface of the coupling portion **81**. The heat conducting sheet **83** serves to prevent the formation of a gap between the support unit **40** and the coupling portion **81** so as to prevent a reduction in heat conductivity.

It has been illustrated and described that the heat dissipation fins **82** are provided on the bottom surface of the heat dissipation plate **80**. However, the heat dissipation fins **82** may not be used and the bottom surface may be subjected to a mirror surface treatment to be used as a reflection plate.

The heat dissipation plate **80** reflects the light passing through the lampshade **70** after emitted from the LEDs of the upper substrate **20** downward again, which may provide a more beautiful illumination effect.

In addition, since the fins **82** formed on the heat dissipation plate **80** refract and diffract light, various illumination effects may also be created depending on the shape of the heat dissipation fins **82**. The heat dissipation fins **82** may also be provided on the top surface of the heat dissipation plate **80**.

As described above, according to the present disclosure, heat is dissipated through the side surface of the substrate support unit **30** that supports the lower substrate **10** and the upper substrate **20** and the heat is transferred and dissipated to the outside of the spherical cover configured by the upper cover **60** and the lower cover **50** through a heat dissipation path continued from the substrate support unit **30** to the support part unit **40** and the heat dissipation plate **80**. As a result, the heat dissipation property may be further improved.

In the foregoing, although the present disclosure has been described in detail with reference to exemplary embodiments, the present disclosure is not limited to the exemplary embodiments and may be variously modified within the scope of the claims, the detailed description of the present disclosure and accompanying drawings. Such modifications belong to the scope of the present disclosure.

The present disclosure relates to a spherical lamp using LEDs which is configured to facilitate dissipation of heat emitted from the LEDs. As a result, the present disclosure may extend the lifespan of the spherical lamp and has industrial applicability.

The invention claimed is:

1. A spherical lamp facilitating heat dissipation, the spherical lamp comprising:
lower and upper substrates, on each of which a plurality of LEDs is mounted;

a plate-shaped substrate support unit having bottom and top surfaces, to which the lower and upper substrates are coupled, respectively;

lower and upper semi-spherical covers positioned on and fixed to the bottom and top surfaces of the plate-shaped substrate support unit, respectively;

a hollow support unit coupled to a central portion of the top surface of the plate-shaped substrate support unit that extends vertically upward through a central portion of the upper semi-spherical cover; and

a heat dissipation plate positioned above the lower and upper semi-spherical covers having a coupling portion with a recess that extends vertically downward from a bottom surface thereof,

wherein an end portion of the hollow support unit is disposed within and fixed to the recess of the coupling portion, and

wherein a circumferential surface of the substrate support unit is exposed to the outside between the lower semi-spherical cover and the upper semi-spherical cover, the circumferential surface is disposed a plurality of heat dissipation fins.

2. The spherical lamp of claim 1, wherein the plate-shaped substrate support unit has a diameter larger than the diameters of the lower substrate and the upper substrates, the plate-shaped substrate support unit includes a plurality of coupling holes formed vertically therethrough to peripheral edges of the lower and upper semi-spherical covers, and a side surface of the plate-shaped substrate support unit is exposed to the outside between the lower and upper semi-spherical covers.

3. The spherical lamp of claim 2, wherein the exposed side surface of the plate-shaped substrate support unit is provided with the heat dissipation fins.

4. The spherical lamp of claim 1, wherein the plate-shaped substrate support unit, the hollow support unit, and the heat dissipation plate are all made of a metal.

5. The spherical lamp of claim 1, wherein an inner surface of the recess of the coupling portion abuts the end portion of the hollow support unit via a heat conducting sheet disposed therebetween.

6. The spherical lamp of claim 5, further comprising a lampshade fitted on the hollow support unit between the upper cover and the heat dissipation plate, wherein the lamp shape reflects or partially transmits light.

7. The spherical lamp of claim 6, wherein the heat dissipation plate has a disc shape and at least one surface of the heat dissipation plate is provided with the heat dissipation fins.

8. The spherical lamp of claim 1, wherein the upper semi-spherical cover includes a through hole disposed on the exterior surface through which the hollow support unit extends therethrough.

9. The spherical lamp of claim 1, wherein the plate-shaped substrate support unit and the hollow support unit are integrally formed.

10. The spherical lamp of claim 1, wherein the coupling portion disposed at the central portion of the bottom surface of the heat dissipation plate has an inclined side surface that increases the inner diameter of the coupling portion toward the outside.

11. The spherical lamp of claim 1, wherein the plate-shaped substrate support unit is configured to be electrically connected to the pendant via the hollow support unit, a through hole disposed in the coupling portion and the heat dissipation plate.
